UNITED STATES PATENT OFFICE

168,891

HANDBAG

Rubin Goldberg, Great Neck, N. Y.

Application November 18, 1952, Serial No. 22,356

Term of patent 3½ years

(Cl. D87—3)

To all whom it may concern:

Be it known that I, Rubin Goldberg, a citizen of the United States, residing at Great Neck, Long Island, New York, have invented a new, original, and ornamental Design for Handbags, of which the following is a specification, reference being had to the accompanying drawing, forming part thereof.

I claim:

The ornamental design for a handbag, substantially as shown.

RUBIN GOLDBERG.
